(57) **CLAIM**

The ornamental design for a bedding foot pocket, as shown and described.

DESCRIPTION

FIG. 1 is a perspective view showing the new, original, and ornamental design of a bedding foot pocket;

FIG. 2 is a front elevation view thereof;

FIG. 3 is a rear elevation view thereof;

FIG. 4 is a left elevation view thereof;

FIG. 5 is a right elevation view thereof;

FIG. 6. is a top plan view thereof; and,

FIG. 7 is a bottom plan view thereof.

The dash-dash broken lines shown in FIGS. 1, 6, and 7 depict portions of the bedding foot pocket that form no part of the claimed design.

1 Claim, 4 Drawing Sheets
